OF MINNESOTA

BOX MAKING MACHINE

Application filed October 31, 1931. Serial No. 572,364.

The present invention relates to a box making machine, and more particularly to a machine for making boxes having an indented side, such as a heart-shaped box.

Various mechanisms have been devised in the past for the fabrication of boxes of the type referred to in the present specification, but most of these mechanisms had certain features which were not fully satisfactory. By departing from the usual practices the present invention is an attempt to eliminate some of the undesirable features of the prior mechanisms.

An object of the present invention is to make an improved and simplified mechanism for the manufacture of heart-shaped boxes.

In order to attain this object, there is provided, in accordance with one feature of the invention, a traveling die, having instrumentalities embodied therein to receive and shape a box wall and having means arranged at suitable points in the path of travel of said die, to adhesively attach a bottom member to said wall and to hold said bottom member under pressure against a flanged edge portion of said wall until the adhesive has set, and finally eject the completed box from said die and prepare the die for the reception of a successive box wall.

These and other features of the invention will be more fully set forth in the following description and the accompanying drawings, wherein:

Figure 1 is a view in side elevation of a mechanism embodying the present invention.

Figures 2 and 3 are plan views on an enlarged scale of the left and right halves, respectively, of the mechanism shown in Figure 1.

Figure 4 is an enlarged sectional view on the line 4-4 of Figure 3.

Figure 5 is a still further enlarged sectional view of a slidably mounted and vertically movable wall flanging die and associated mechanism, showing the parts in normal position in solid lines and in operated position in dotted lines.

Figure 6 is a plan view of the portion of the mechanism shown in Figure 5.

Figure 7 is an enlarged view of a detail showing of a flanged box cover holding arm.

Figure 8 is an enlarged plan view of a forming die shown open in solid lines and closed in dotted lines.

Figure 9 is an enlarged view of the face of a portion of a presser belt with a die positioning bar secured thereto transversely thereof, and a cover embossing member secured to the belt face.

Figure 10 is a sectional view on the line 10-10 of Figure 9.

Figure 11 is a sectional view on the line 11-11 of Figure 8.

Figure 12 is a bottom view of the right hand end of the mechanism shown in Figure 1.

Figure 13 is a view in side elevation of a knockout operating cam with a die in the position it occupies just before engaging said cam; and

Figures 14 and 15 are sectional views of edge portions of a box and cover, respectively, of a type of box fabricated by the present mechanism.

Referring to the drawings in detail, a frame A comprises legs 1 connected at their upper ends to angle iron side frame members 2. Shaft hangers 3 and 4 are mounted below the frame members 2 to support shafts 5 and 6 for rotation therein. Mounted on each of the shafts 5 and 6, are a pair of sprocket wheels 7 spaced apart to receive link belts 8 and 9. The sprockets mounted on the shaft 5 are keyed thereto, so as to be driven thereby, while the sprockets on the shaft 6 may turn freely thereon. The sprockets are mounted so as to have their tops flush with the top frame members 2.

Angle iron frame members 10 are mounted below the upper frame members and in line with the lower sides of the sprockets 7 on each side, so as to support the lower runs of the chains 8 and 9, and forming dies B carried thereby.

An electric drive motor 11 (see Figure 1) is mounted on a support member 12 connected to the frame and is arranged to drive a

pulley 13 by means of a belt 14. This pulley is mounted on the same shaft with a pulley 15, which in turn drives a pulley 16 by means of a belt 17.

5 An operating handle 18 is pivotally mounted on the front side of the frame and carries an idler pulley 19 to engage the belt 17. A toothed segment 20 is mounted concentrically with the pivotal support of the 10 operating lever, and a pawl 21 connected to a hand grip member 22 holds the operating lever 18 in adjusted position. Moving the lever 18 to the left to the position shown in Figure 1, moves the idler pulley 19 upward 15 to tighten the belt into driving engagement with the pulleys, which it encircles, while moving the lever 18 to the right, loosens the belt and releases it from driving engagement with its pulleys. Intermediate speed 20 reducing sprockets and chains are connected between the pulley 16 and the shaft 5 to drive the shaft 5 and the sprockets 3 and chains 8 and 9 thereby.

Shaft hangers 23 are mounted above the 25 left end portion of the frame, as shown in Figure 1, and in these hangers are rotatably mounted shafts which support sprockets 24, around which are mounted chains 25. A belt 26, which may be of leather, is affixed between the inner edges of the chains 25, so that the chains 25 form marginal edges of the belt. A presser roll frame 27 is mounted above the lower run of the belt and spring 30 adjusting screws 28 are mounted to control the pressure on said frame. The presser roll frame is of a type well known to the art, comprising rollers 29 mounted to rotate freely between sides of the presser frame 27, and it will, therefore, be unnecessary to burden the present specification with a detailed description of it.

A plurality of forming dies B are carried by the chains 8 and 9, and for the following 45 detailed description thereof, particular reference is made to Figures 8, 11, and 12.

A base plate 30 is provided with a pair of threaded openings in the bottom thereof in which bolts 31 are screwed to secure special links 32 and 33, provided therefor in the 50 chains 8 and 9, respectively, to said plate. Secured, one adjacent each of the front and rear edges of the upper surface of the base plate 30, a pair of parallel, undercut guides 34 and 35. Slidably mounted between these 55 guides are a pair of forming die members 36 and 37.

Each of these members is provided with flanges 38 and 39 adapted to ride in the undercut portions of the guide members 34 60 and 35 to permit slidable movement of said die members therein. Each die member is provided with a pair of downwardly projecting studs 40 which extend through slotted 65 openings 41 provided therefor in the base plate 30. Mounted on the lower ends of the

studs 40 of each die member is a bar 42. Pivotally mounted on the center of the bottom of each of the bars 42 is a roller 43 which engages cam tracks mounted between the chains 8 and 9 and which will later be described in detail to open and close the dies at the proper points in their travel.

A central forming die 44 of the size and shape of the interior of the boxes to be made on the mechanism, is affixed to the upper surface of the base plate 30 centrally of the opening in the slidably mounted dies 36 and 37, when said dies are in their closed position, as indicated in dotted lines in Figure 8. The clearance between the inner die 44 and the outer dies 36 and 37, when closed, should be about the thickness of the cardboard to be used in making the boxes which the machine is designed to fabricate.

A knockout pin 45 is slidably mounted in a hole drilled centrally of the central forming die 44 and extending through the base plate 30. The knockout pin 45 is provided with an enlarged head portion 46 which normally rests in a recess provided therefor in the top of the central forming die, to lie flush with the upper surface thereof. Tension coil springs 47 and 48 are mounted between the side portions of the slidable outer die members 36 and 37 to resiliently draw them together.

Mounted, one on the outer end of each of the outer or movable die members 36 and 37, are cover positioning fingers 49 and 50 to hold a flanged cover blank in position therebetween. These positioning fingers are preferably formed of spring brass and are each secured to spring steel strips 51 and 52, respectively. One end of each of the spring steel strips 51 and 52 is secured tightly to the outer end of the die upon which it is mounted, while the other end thereof is provided with a slotted opening 53 which is secured to the die member by a screw 54 to permit relative longitudinal movement of this end of the strip with respect to the screw 54. A coil compression spring 55 is mounted beneath the center of each of the strips 51 and 52 to normally arch said strips upwardly. This construction permits the 115 spring strips to flatten out under the pressure to which they are subjected, while passing beneath the presser rolls.

The cam tracks which engage the rollers 43 to open and close the movable dies are in two pairs. One pair 56 and 57 are the die opening tracks, and the pair 58 and 59 are the die closing tracks. The die opening tracks 56 and 57 are mounted on cross brace members 60 secured transversely of the frame. These tracks are shaped and mounted to lie parallel with the plane of the chains 8 and 9, the tracks being curved around the right hand end of the frame as shown in Figures 1, 3, and 12 to conform 130

with the plane of the chains as they pass around the sprockets 7. The ends of the lower portions of these tracks are bent inwardly as at 61 and 62, best shown in Figure 12, to engage the die operating rollers 43, as the forming die passes these portions, to force the movable dies apart and release them from engagement with a completed box carried on the fixed central die member 44.

A knockout cam 63 is mounted between the die opening portions 61 and 63, to engage the lower end of the knockout pin 45 and force it in, thereby forcing the completed box carried on the central form 44 off of said form. This action takes place after the opening of the movable dies 36 and 37.

The die closing tracks 58 and 59 are positioned in parallel spaced relation along the top of the frame at a height to engage the die operating rollers 43. It will be noted from Figures 2 and 3 that the die closing track 58 curves inwardly at 64 ahead of the point, in the travel of the die, at which the other die closing track 59 curves inwardly at 65. This closes the die 36 over the convex end of the stationary central die, prior to the closing of the die 37 over the indented end of the stationary die.

The closing tracks 58 and 59 preferably terminate just beyond the presser rolls 29, as shown in Figure 2, since from this point on the tension of the springs 47 and 48 is sufficient to hold the movable dies closed to hold the box in position in the die.

A crimping and glue spreading mechanism is mounted above the frame A and is shown generally in Figures 1 and 3, and in detail in Figures 4, 5, and 6.

This mechanism is for crimping inwardly the upper edge of the box wall, as shown at 66 in Figures 14 and 15, and applying paste to the exposed face of said flange, and also to the exposed face of a heart-shaped cardboard blank 67, shown in Figures 14 and 15, respectively.

The wall crimping mechanism comprises two side frame members 68 and 69, and transverse frame members 70 and 71. The pair of parallel, longitudinally disposed rods 72 and 73 are mounted between the transverse frame members 70 and 71, and upon these rods are slidably mounted a pair of transversely positioned carriage supports 72^a and 73^a, which support a crimping die carriage generally referred to as C. Four posts 74 are slidably mounted in vertical openings, two in each of the supports 72^a and 73^a, the lower ends of said posts being rigidly secured to a crimping die base plate 75. A coil spring 76 is mounted around each of the posts 74 and is held in compression as by means of a nut 77 and cotter pin 78 to normally hold the base plate 75 closely against the lower faces of the supports 72^a and 73^a.

Coil springs 79 and 80 (see Figure 6) are connected from the transverse frame member 71 to angle iron side members 81 and 82 connected to the ends of the transverse support members 72^a and 73^a. These springs normally hold the carriage C rearwardly against a pair of shock absorbing springs 83 and 84, which encircle the rods 72 and 73, respectively.

Pivotedly mounted below the angle iron side members 81 and 82 are lever arms 85 and 86. These lever arms are bent outwardly at their rear ends as at 87 and 88 (see Figure 6) and downwardly at their forward ends as at 89 (see Figures 4 and 5).

The outwardly bent rear ends 87 and 88 are mounted to be in horizontal alignment with arms 90 and 91 secured to the stationary side frame members 68 and 69, respectively, so that when the carriage moves forwardly to bring the outwardly bent end portions 87 and 88 of the lever arms 85 and 86 into engagement with the arms 90 and 91, the rear ends of the lever arms will be forced inwardly thereby, causing the downwardly bent forward ends of the lever arms to separate.

The downwardly bent forward ends of the lever arms 85 and 86 are positioned to engage the forward side of a forming die B, as the forming die passes thereunder, and thereby move the carriage C along with the forming die until the lever arms are actuated by the stationary arms 90 and 91 to separate the downwardly bent forward ends of the lever arms 85 and 86 to release them from engagement with the forming die, whereupon the springs 79 and 80 restore the carriage C to the solid line position of Figure 5.

A crimping die 92 (see Figure 5) is secured to the lower face of the plate 75 and is formed with a heart-shaped recess therein of a size and shape to conform to that of the wall of the box being formed when said wall is gripped in the forming die.

A cam block 93 is mounted on the plate 75 so that when the carriage C is in its forward position, as indicated in dotted lines in Figure 5, said cam block will be positioned directly below a rotating cam 94 fixedly mounted on a shaft 95 above the frame A. The shaft 95 is driven by a chain 96 which is connected to the driving mechanism and is timed so that the cam 94 will be rotated to engage the block 93 once each time a forming die passes thereunder. The drive chain to the cam shaft 95 is somewhat slack and an idler pulley 97 is mounted on a pivoted arm 98 with a coil spring 99 (see Figure 4) to hold the idler in resilient engagement with the chain. The cam 94 is rotated in the direction of the arrow in Figure 4 and is timed so that the forming die B will be released by the separating of the lever arms 85 and 86 just after the cam 94 has passed

bottom dead center. The cam block 93 will be drawn back with the carriage C upon which it is mounted by means of the coil springs 79 and 80 and will exert a rotative force on the cam 94 in the direction of the arrow in Figure 4. If rigid drive means were employed, this would retain the carriage C momentarily in the position indicated by the dotted line in Figure 5. However, by means of the slack in the drive chain 96, a limited movement of the cam 94 in the direction of the arrow is permitted and the carriage C is free to slide back to the solid line position shown in Figure 5.

15 The crimping die 92 is positioned on the plate 75 so that when the downwardly bent forward ends 89 of the lever arms are engaged by the forward edge of the forming die, the crimping die will lie directly above 20 and in register with the upper edges of the box wall carried therein, and, as the carriage C is carried forward by the engagement of these downwardly turned ends of the levers, the carriage will remain in this 25 relative position until released by the spreading of the levers. As the cam block 93 comes beneath the cam 95, the cam 95 engages the cam block as indicated in dotted lines in Figure 5, and forces the plate 75 30 and with it the crimping die 92 downwardly to the dotted line position. The crimping die crimps the upper edges of the box walls inwardly, as shown at 66 in Figures 14 and 15.

35 As the strip of cardboard forming the box wall is inserted in the forming die, a heart-shaped piece of cardboard is inserted within the wall to lie on top of the stationary inner die 44. Thus, when the upper 40 edges of the walls are crimped down they are crimped over the edge of this heart-shaped cardboard member.

The gluing mechanism shown in plan view in Figure 3 and sectionally in Figure 4, comprises a glue trough 100 mounted between the side frame members 68 and 69, with a roller 101 pivotally mounted transversely of said glue trough and positioned so that the lower portion of this roller 50 is partially immersed in glue contained in said glue trough in a liquid form.

A spreading roller 102 is pivotally mounted adjacent the glue roller 101 so that as the glue is carried up from the trough 100 55 it will pass between the spreading roller and the glue roller 101. The spreading roller is mounted in movable blocks 103 and adjusting screws 104 are threadedly mounted in brackets 105 to adjust the pressure on 60 the spreading roller 102. By screwing these adjusting screws in, pressure on the spreading roller against the glue roller will be increased, thereby decreasing the amount of glue which is carried around by the glue 65 roller. By decreasing the pressure on this

spreading roller, the amount of glue carried around by the glue roller may be increased. The glue roller is in peripheral engagement with a roller 106 positioned to engage a side thereof, and this roller is in 70 turn in peripheral engagement with a roller 106 which is positioned vertically beneath said roller. This second roller carries the glue down to where it engages the upper 75 surface of the inwardly turned flanges of the box walls and the heart-shaped blank 67 which is gripped beneath said inwardly turned wall edge portions and spreads a layer of glue over these members.

The belt 26 which passes beneath the presser rolls 29 is provided with cross strips 111, as shown in Figures 2, 9, and 10. These cross strips engage the forward edges of the forming dies as they pass beneath the belt 26 and serve to advance the belt 26 at the same speed as the forming dies are traveling. The forming dies are disposed in alternate rotation with first a box forming die and then a cover forming die. The box 80 portions and the cover portions are substantially identical, except that the cover portion is of a slightly larger diameter so as to telescopically fit over the box portion and the cover portion is preferably crowned, 85 as shown in Figure 15.

In order to produce this crowning effect the cover die is preferably upset slightly in its central portion, as shown at 108 in Figure 15, and a cut-out member 109, which may be of leather, is adhesively secured to the belt 26 with a heart-shaped cut-out portion 110 centrally thereof. The cut-out portion 110 is of a size to engage only the edge portions of the box cover. This causes an embossing or crowning effect, as shown at 108 in Figure 15. As the forming die passes beneath the belt 26 which is held downwardly into pressing engagement with the box by means of the pressing rolls 29, the parts of the box being formed are held into closely compressed condition long enough for the glue to initially set.

The operation of the mechanism is as follows, and this portion of the description may best be followed by referring principally to Figure 1:

As a forming die B passes upwardly around the right hand end of the mechanism, the movable forming dies will be held in the open position, as shown in Figure 8, by means of the cam tracks 56 and 57. At this point of the forming die's travel, the operator inserts a preformed circular strip of cardboard over the stationary central die member 44, this strip of cardboard being 120 of a width slightly higher than that of the stationary die member, and having a circumference equal to that of the periphery of the heart-shaped die member 44. At the same time the operator also inserts the 125

70

75

110

115

120

125

130

heart-shaped sheet 67 of cardboard of the same size and shape as the top surface of the stationary die member 44.

As the die closing roller 43 engages the curved portion 64 of the closing cam track 58, the die member 36 is moved inwardly to force the strip of cardboard into conformity with the convex pointed end of the die 44. As the other cam operating roller 43 passes the inwardly bent portion 65 of the cam track 59, the strip of cardboard which is to form the box wall, is pressed into conformity with the indented end of the stationary die 44, thereby bringing the box wall into complete peripheral engagement with the heart-shaped cardboard sheet 67 placed on top of the stationary die 44, as previously described. The die travels forward with the parts in this position until the forward edge of the forming die engages the downwardly bent portions 89 of the lever arms carried by the die supporting carriage C. The forming die B moves the carriage C forwardly beneath the cam 94. The cam 94 is rotated by its operative mechanism to engage the cam block 93 and depress the crimping die 92 to the dotted line position of Figure 5, thereby crimping inwardly the upper edge of the box wall to overlie the cardboard 67 as indicated in Figures 14 and 15. As the carriage C reaches its extreme forward position, the downwardly bent lever arms are spread apart by the arms 90 and 91, releasing the carriage C which is thereupon returned to its normal, or dotted line position, as shown in Figure 5, by means of the coil springs 79 and 80, as shown in Figure 6.

The forming die then passes beneath the glue roller 107 which spreads a layer of glue over the exposed faces of the crimped edge portions 66 and the cardboard blank 67. After the forming die, with the box walls and blank 67 pass beyond the glue rollers the operator places in position a flange bottom member 112 which is guided to its proper position by the fingers 49 and 50, best shown in Figures 8 and 11. The forming die then passes beneath the belt 26, the forward edge of the forming die engaging the cross strip 111. The belt, in conjunction with the presser rolls 29, presses the flange bottom member 112 downwardly on the glued surfaces of the wall flange 66, and the cardboard blank 67, to adhesively secure the flange bottom member 112 into position thereon. A quick setting glue is preferably used so that after the forming die B passes beyond the belt 29 the flange bottom member 112 will remain adhesively secured in position.

The forming die B with the box held therein passes downwardly around the sprocket 5 on the left end of the machine, the coil springs 47 and 48 (see Figure 8)

holding the movable dies 36 and 37 in engagement with the box wall sufficiently to hold the box in position upon the stationary center die member 44. The box is then carried along the lower run of the chains 8 and 9, traveling to the right, as indicated in Figure 1, until it reaches the die opening tracks 56 and 57 (see Figure 12) whereupon the movable dies 36 and 37 are spread apart and the knock-out pin 45 is engaged by the cam 63 to force the knock-out pin (see Figure 11) downwardly, thereby stripping the box from the central forming die.

The empty forming die then passes upwardly around the right hand end of the machine, as shown in Figure 1, with the forming dies open and ready to receive another wall blank and cardboard blank 67. The same procedure is followed for both the boxes and the covers with the exception, as hereinbefore pointed out, that the crowning of the box cover is accomplished by the cut-out forms on the belt.

Inasmuch as this general type of box is well known to the art, it has been believed to be unnecessary to show the box structure more fully than is illustrated in Figures 14 and 15.

We claim:

1. A box-making machine, comprising, in combination, a traveling conveyor, box wall forming dies carried by said conveyor and adapted to receive a box wall member therein, cam means mounted to operate said dies to perform a forming operation on a box wall contained therein, a wall flanging device co-operatively associated with said dies to form a flange on a box wall formed in said dies, adhesive spreading mechanism mounted to spread a layer of adhesive on a flanged box wall to adapt said flange to adhesively receive a top, and presser means adapted to engage a top positioned on said flange and exert pressure thereon.

2. A box making machine, comprising a conveyor, drive means adapted to impart a continuous motion thereto, box wall forming dies mounted thereon and adapted to receive a box wall band therein, die operating means mounted to operatively engage said dies during movement thereof to form said box band in conformity with said dies, means mounted to engage said box wall to bend an edge portion thereof to receive a box bottom member, and presser means mounted beyond said wall bending means to press a box bottom member into engagement with said bent wall edge portion.

3. In a box making machine, a movable conveyor, means mounted to continuously drive said conveyor in a recurring cycle, box wall forming dies carried by said conveyor, said forming dies being adapted to receive a box wall band, cam tracks mounted to operatively engage said forming dies to form

said wall band into conformity with said dies, wall flanging means co-operatively associated with said dies to bend a flange on a box wall carried by said dies at a predetermined point of travel thereof to adapt said wall to be adhesively secured to a top, and presser means mounted beyond said flanging means to exert a pressure on a top mounted on said flange.

19 4. In a box making mechanism, a movable conveyor, drive means connected thereto to continuously drive said conveyor in recurring cycles, a central forming die mounted on said conveyor, a pair of slideable dies mounted laterally adjacent said conveyor and adapted to receive a box wall band between said central die and said movable dies, and cam tracks mounted adjacent said conveyor and adapted to operatively engage said movable dies to force a box band into conformity with said central die.

5 5. A box making machine of the character described comprising a movable forming die adapted to receive a box wall band therein, drive means mounted to move said die

continuously in a recurring cycle, a flanging die mounted to engage a box wall carried in said forming die at a predetermined point in the cycle of movement thereof to form a flange on an edge thereof to receive a top thereon, and presser means mounted to engage a top placed on said flanged portion to press said top into close engagement with said flange.

6. In a box making mechanism, the combination with a driven conveyor, having box wall forming dies thereon and adapted to receive and form a box wall, of means for gluing a top on a box wall held in said forming die, and a presser belt mounted above said die and having positioning means adapted to be engaged by said die to position said die in a predetermined position with respect to said belt and to move said belt in unison therewith.

In testimony whereof we affix our signatures.
